[57] CLAIM

The ornamental design for an ashtray, as shown and described.

DESCRIPTION

FIG. 1 is a perspective view of an ashtray showing our new design;

FIG. 2 is an elevational view thereof;

FIG. 3 is a sectional view thereof taken along line 3—3 of FIG. 1;

FIG. 4 is a top plan view thereof.

The broken line disclosure of the indicia of FIG. 2 is for illustrative purposes only and forms no part of the claimed design.

FIG. 1

FIG. 2

FIG. 3

FIG. 4
